UNITED STATES PATENT OFFICE

CHARLES A. TOCE, OF HOUSTON, TEXAS

DESIGN FOR A GAME TABLE

Application filed August 8, 1931. Serial No. 40,805. Term of patent 7 years.

To all whom it may concern:

Be it known that I, CHARLES A. TOCE, a citizen of the United States, residing at Houston, in the county of Harris and State of Texas, have invented a new, original, and ornamental Design for a Game Table, reference being had to the accompanying drawing, forming a part thereof.

The figure is a perspective view of a game

table, showing my new design. The side of the table opposite from that shown by the drawing is plain and unornamented.

I claim:

The ornamental design for a game table, as shown and described.

In testimony whereof, I hereunto affix my signature.

CHARLES A. TOCE.
